UNITED STATES PATENT OFFICE.

J. F. LEITCH, OF GREENE, NEW YORK, ASSIGNOR TO ORRIN D. CARTER.

IMPROVED FAN-BLOWER.

Specification forming part of Letters Patent No. 34,028, dated December 24, 1861.

To all whom it may concern:

Be it known that I, J. F. LEITCH, of the town of Greene, in the county of Chenango, State of New York, have invented a new and useful Improvement in Fan-Blowers for Furnaces, Forges, Blacksmith-Fires, or any place where a constant and steady current of wind is desired; and the following is a clear, full, and exact description of the same, reference being had to the accompanying drawings, making a part of this specification.

Figure 1 shows a top view or section cut through at the center of fan-room. Fig. 2 is a side elevation, having one plate removed, showing the internal arrangements.

My invention consists in the peculiar construction of and combination of the circumscribed fan-room, scroll air chamber and passage, and wind cut-off.

To enable others skilled in the art to make and use my invention, I will describe it in detail, referring to the drawings and to the letters marked thereon.

In constructing my improved fan-blower for furnaces, forges, blacksmith-fires, or any places where a constant and steady current of air is desired, the case may be made of cast metal by having the two side patterns furnished with the rim and flange to match and come together so as to form the circular fan-room, scroll air-passage, and wind cut-off; or they may be made of sheet or boiler iron, the flange to form the circumscribed fan-room and outside case to the scroll being bent in the proper shape, and may be riveted or bolted onto the sides and secured together, or the case can be constructed in part or entirely of wood.

The sides A A are to be flat surfaces and placed parallel to each other, between which the outer rim of the case B is secured in such manner as to form an air-tight joint. The rim B may be of any desirable width, to give capacity to the amount of wind required; but it is not desirable that the space in the scroll-chamber C should be wider than to form a

square of the size of the conductor D or pipe to convey the current of wind from the blower. The fan-room E is made in a circle by having a rim or flange a a secured to the sides A A and extending toward each other, so that they fill about three-fourths of the space between the sides A A, thus forming a partition between the fan-room E and the scroll air-passage C, with the exception of a narrow opening or slit b b in the center, which extends around the entire fan-room E, it only being closed at one point and forming a wind cut-off e directly at or where the scroll commences, thereby preventing any current of wind from being carried around by the wings f f f f of the revolving fan F. The wings f f f f are made square or oblong, are slightly curved or bent forward, and should nearly fill all of the space in the circumscribed fan-room E beyond the holes or openings c c in the sides A A, which are for the ingress of the air to the blower.

The fan F may be operated by a band or belt on the driving drum or pulley G on the shaft h in the ordinary manner.

The advantages and peculiarities of my invention are that it does not require more than one-fourth the power to run it to raise the same amount of blast that it takes for all others that have ever come to my knowledge, and, moreover, it operates silently, not producing that monotonous humming incident to all others, and it can be made as cheap or cheaper than any other known or used.

Having thus fully described my invention, what I claim as new, and desire to secure by Letters Patent, is—

The circumscribed fan-room, scroll air-passage, and wind cut-off, all in combination, substantially as and for the purposes specified.

J. F. LEITCH.
